Design No. 12,222, dated April 12, 1881.

UNITED STATES PATENT OFFICE.

JOHN McLEAN, OF BROOKLYN, NEW YORK.

DESIGN FOR A FENCE.

SPECIFICATION forming part of Design No. 12,222, dated April 12, 1881.

Application filed March 1, 1881. Term of patent 3½ years.

To all whom it may concern:

Be it known that I, JOHN McLEAN, of Brooklyn, in the county of Kings and State of New York, have invented a new and original Design for Fences, of which the following is a specification.

This invention relates to a new and original design for fences or other similar structures; and it consists in the novel figures and grouping hereinafter more fully described.

The accompanying cut represents a face view of my new design.

From a vase-shaped figure, *a*, projects the stem *b*, bearing leaves and a star-like flower; also the two stems *c c'*, bearing curling leaves. These figures form the group A. This vase *a* stands on a cross-bar, *G*, with pendent projections, which connects the two side bars or columns, *B B'*, near their lower ends. Between the columns *B B'* is the curving bar *D*, partly supported upon the stems *b c c'*, and having the ends of the stems *c* and *c'* projecting through it. Upon and above this bar *D* is the ornamental figure *E*, resembling a flower, with branches projecting on each side thereof. From the ends of the bar *D* run the curving

leaf-like figures *d d'*, and the ends of the bar *D* are connected with the vase *a* by the hanging garlands *e e'*.

The effect of the design is that of a frame, 30 with a straight bottom and sides and a curving ornamented top, inclosing a vase, from which project the leafy stems described.

I claim—

1. The design for fences, consisting of the group A, containing figures *a b c e'*, substantially as shown.
2. The design for fences, consisting of the figures *G B B' D*, substantially as shown.
3. The design for fences, consisting of the figure *E*, substantially as shown.
4. The design for fences, consisting of the group A, containing figures *a b c c'*, and figures *D E d d' e e'*, substantially as shown.
5. The design for fences, consisting of the group A, containing figures *a b c c'*, and figures *D E B B' G' d d' e e'*, substantially as shown.

JOHN McLEAN.
